PORATION OF OHIO.

VARIABLE-SPEED MECHANISM.

1,090,484.

Specification of Letters Patent. Patented Mar. 17, 1914.

Application filed April 12, 1913. Serial No. 760,672.

To all whom it may concern:

Be it known that we, RICHARD K. LE BLOND and WILLIAM F. GROENE, citizens of the United States, residing at Cincinnati, county of Hamilton, and State of Ohio, have invented certain new and useful Improvements in Variable-Speed Mechanism, of which the following is a full, clear, and exact specification.

10 This invention relates to variable speed mechanism especially designed for use in all geared headstocks of machine lathes.

The principal object of the invention is to provide improved and simplified mechanism 15 for driving a spindle at different speeds by employing only two shafts in addition to the spindle and driving shaft.

It is also our object to so construct and arrange the "back gear" driving mechanism 20 that it will be both simple and inexpensive to manufacture and easy and reliable in operation.

Other objects will appear as the description proceeds.

25 The invention will be first described in connection with the accompanying drawings, which constitute a part of this specification, and then set forth more specifically in the claims at the end of the description.

30 In the accompanying drawings, in which the same reference characters are used to designate similar parts throughout all the views: Figure 1 is a longitudinal section of a lathe headstock provided with our improved 35 gearing, the section being taken through the spindle, intermediate shaft and driving shaft as indicated by the line 1—1 in Fig. 3; Fig. 2 is a longitudinal vertical section through the spindle and back gear shaft on 40 the line II—II of Fig. 3; Fig. 3 is a vertical cross section on the line III—III of Figs. 1 and 2, and Fig. 4 is a front elevation of the headstock on a reduced scale.

The driving shaft A, which is actuated by 45 a drive pulley a, Fig. 1, carries cluster gears a', a² and a³, splined to said shaft, and adapted to selectively mesh with gears b', b² and b³ on the intermediate shaft B. Said cluster gears may be shifted by turning a 50 crank C on the front of the casing D, of the headstock, the crank C being attached to a rock shaft e also carrying an arm e' provided with a shoe e² engaging the groove a⁴ in the cluster gears.

55 The gears b', b² and b³ are keyed to the in-

termediate shaft B. The first two of these gears may be integral, and the third separate, as illustrated. The intermediate shaft also carries another gear b which may be cut in the shaft between the gears b', b² and 60 b³. This gear b is constantly in mesh with a gear e loose on a sleeve E which is itself loosely mounted around the spindle F. The gear b' is constantly in mesh with another gear e' loose on the sleeve E.

65 The gears e and e' are equipped with clutch members, preferably positive clutch members e² and e³, respectively, facing each other. Splined on the sleeve E between said gears is a spool G having clutch members 70 g and g' which are supplemental to the clutch members e² and e³, respectively. The spool G may be shifted on the sleeve so as to bring either one of its clutch members into 75 operative engagement with the corresponding clutch member of one or the other of said gears, by any suitable means, such as a hand lever H carried by a stud h provided with a yoke h' having a shoe h² engaging the groove g² in said spool.

80 From the foregoing it will be seen that the intermediate shaft may be driven at three different speeds from the driving shaft by reason of the cluster gears being adapted to mesh selectively with the gears b', b² and b³ on said intermediate shaft, and that each of said three speeds of the latter shaft may be transmitted to the sleeve E at two different speeds on account of the meshing of the gears b and e, and b' and e', respectively, 85 either of said gears e or e' being adapted to be locked to said sleeve by properly shifting the spool G. Hence the sleeve E may be driven from the driving shaft at six different speeds.

86 The sleeve may be coupled directly with the spindle to get the six "open" drives of the latter, or said spindle may be driven from the driving shaft indirectly through the back gear shaft K, to get six additional, 100 or "back gear" drives, making twelve changes of speed in all. As here shown, the direct connection between the sleeve and spindle consists of a clutch member l on a gear L, keyed to the spindle, and a supplemental clutch member m on a spool M splined on the sleeve.

105 The "back gear" drives are obtained by employing the back gear shaft K on which is mounted a gear k constantly in mesh with 110

the gear e' and a gear k' adapted to mesh with the gear L . The gear k may be keyed to a bushing k^2 which is splined on the shaft K , and the gear k' may be fast on said shaft, so that in order to move the gear k' into and out of mesh with the gear L the whole shaft is movable axially.

Now it is obvious that the direct connection between the sleeve and spindle must be severed before the back gears are brought into play, and vice versa. We have provided means for accomplishing both of these operations in the proper order and times. This means consists of a hand lever N carried by a stud n also carrying oppositely extending bifurcated arms n' and n'' . The arm n' is provided with a shoe n^3 engaging the groove m' in the spool M . The arm n'' has a shoe n^4 engaging the groove p in a collar P fixed to the shaft K . By reason of this construction, the swinging of the lever N slightly to the right, Fig. 2, will shift the spool M to the right so as to bring its clutch member m into operative engagement with the clutch member l on the gear L which is fast on the spindle, thus throwing in the direct or "open" drive. It will be noted that in this position of the parts, the gear k' is out of mesh with the gear L . Now if the lever N is swung to the left, Fig. 2, the spool M will be shifted to the left and the gear k' and shaft K will be shifted to the right with the result that the clutch member m will be first separated from the clutch member l and the gear k' will then be brought into mesh with the gear L , thus throwing out the direct or "open" drive and throwing in the "indirect" or "back gear" drive. This "back gear" drive from the sleeve to the spindle is through gear e' , gear k , bushing k^2 , shaft K , gear k' , and gear L .

Having thus described our invention what we claim as new and desire to secure by Letters Patent of the United States is:

1. The combination with a spindle, of a sleeve loose thereon, means to drive the sleeve, a clutch member fast on the spindle, a supplemental clutch member splined on the sleeve, whereby the spindle may be driven directly from the sleeve, means for indirectly driving the spindle from the sleeve including a gear fast on the spindle, a back gear shaft mounted to slide in its bearings, a gear fast thereon and adapted to mesh with the gear which is fast on the spindle, constantly intermeshing gears on the sleeve and back gear shaft, and means for shifting the clutch member on the sleeve and for moving the back gear shaft axially.
2. The combination with a spindle, of a sleeve loose thereon, means to drive the sleeve, a gear fast on the spindle, a clutch member on said gear, a supplemental clutch member splined on the sleeve, whereby the

spindle may be driven directly from the sleeve, means for indirectly driving the spindle from the sleeve including the gear fast on the spindle, a back gear shaft mounted to slide in its bearings, a gear fast thereon and adapted to mesh with the gear which is fast on the spindle, constantly intermeshing gears on the sleeve and back gear shaft, and means for shifting the clutch member on the sleeve and for moving the back gear shaft axially.

3. The combination with a spindle, of a sleeve loose thereon, means to drive the sleeve, a clutch member fast on the spindle, a supplemental clutch member splined on the sleeve, whereby the spindle may be driven directly from the sleeve, means for indirectly driving the spindle from the sleeve including a gear fast on the spindle, a back gear shaft mounted to slide in its bearings, a gear fast thereon and adapted to mesh with the gear which is fast on the spindle, a gear on the sleeve, a second gear mounted on the back gear shaft to turn therewith, but held against axial movement with the same so as to constantly mesh with the gear on the sleeve, and means for shifting the clutch member on the sleeve and for moving the back gear shaft axially.

4. The combination with a spindle, of a sleeve loose thereon, means to drive the sleeve, a clutch member fast to the spindle, a supplemental clutch member splined on the sleeve, whereby the spindle may be driven directly from the sleeve, means for indirectly driving the spindle from the sleeve including a gear fast on the spindle, a back gear shaft mounted to slide in its bearings, a gear fast thereon and adapted to mesh with the gear which is fast on the spindle, a gear on the sleeve, a second gear mounted on the back gear shaft and constantly in mesh with the gear on the sleeve, a bushing interposed between said shaft and second gear thereon, said bushing being keyed to said second gear and splined to the back shaft, and means for shifting the clutch member on the sleeve and for moving the back gear shaft axially.

5. The combination with a spindle, of a sleeve loose thereon, means to drive the sleeve, supplemental clutch members on the spindle, and sleeve, one of said clutch members being movable to and from the other, a gear fast on the spindle, a back gear shaft mounted to slide axially in its bearings, a gear fast on said shaft and adapted to mesh with the gear on the spindle, constantly intermeshing gears on the sleeve and shaft, a hand lever, and means for operating the movable clutch and moving the back gear shaft axially by swinging said lever in one direction.

6. The combination with a spindle, of a sleeve loose thereon, means to drive the

5 sleeve, supplemental clutch members on the spindle, and sleeve, one of said clutch members being movable to and from the other, a gear fast on the spindle, a back gear shaft
 10 mounted to slide axially in its bearings, a gear fast on said shaft and adapted to mesh with the gear on the spindle, constantly intermeshing gears on the sleeve and shaft, an intermediately pivoted lever operatively connected at one end with the movable clutch and at the other end with the back gear shaft, and means for swinging said lever for the purpose specified.

15 7. The combination with a spindle, of a sleeve loose thereon, means to drive the sleeve, supplemental clutch members on the spindle and sleeve, one of said clutch members being movable to and from the other, a gear fast on the spindle, a back gear shaft
 20 mounted to slide axially in its bearings, a gear fast on said shaft and adapted to mesh with the gear on the spindle, constantly intermeshing gears on the sleeve and shaft, an intermediately pivoted lever operatively connected at one end to the movable clutch and at the other end to the back gear shaft, and means connected directly to said lever for swinging the same, whereby the clutch
 25 will be moved in one direction and the shaft in the opposite direction, the pivot of said lever being arranged nearer the end which is connected to the clutch in order to give a greater movement to the shaft than to said 50 clutch.

30 20 7. The combination with a spindle, of a sleeve loose thereon, means to drive the sleeve, supplemental clutch members on the spindle and sleeve, one of said clutch members being movable to and from the other, a gear fast on the spindle, a back gear shaft
 25 mounted to slide axially in its bearings, a gear fast on said shaft and adapted to mesh with the gear on the spindle, constantly intermeshing gears on the sleeve and shaft, an intermediately pivoted lever operatively connected at one end to the movable clutch and at the other end to the back gear shaft, and means connected directly to said lever for swinging the same, whereby the clutch will be moved in one direction and the shaft
 30 in the opposite direction.

8. The combination with a spindle, of a sleeve loose thereon, means to drive the sleeve, supplemental clutch members on the spindle and sleeve, one of said clutch members being movable to and from the other, a gear fast on the spindle, a back gear shaft mounted to slide axially in its bearings, a gear fast on said shaft and adapted to mesh with the gear on the spindle, constantly intermeshing gears on the sleeve and shaft, an intermediately pivoted lever operatively connected at one end to the movable clutch and at the other end to the back gear shaft, and means connected directly to said lever for swinging the same, whereby the clutch
 45 will be moved in one direction and the shaft in the opposite direction, the pivot of said lever being arranged nearer the end which is connected to the clutch in order to give a greater movement to the shaft than to said 50 clutch.

In testimony whereof we have signed our names to this specification in the presence of two attesting witnesses.
